UNITED STATES PATENT OFFICE

FELIX JOSEPH VICKI, OF PARIS, FRANCE

FACE POWDER FEEDER

Application filed March 10, 1930, Serial No. 434,698, and in France March 11, 1929. Renewed July 2, 1931.

This invention relates to boxes or containers for feeding face powders and more particularly to an improved face powder feeder constructable either in the form of an ordinary portable powder box such as the one commonly carried by ladies in their hand bags or in the form of a stationary powder feeder adapted to be left on a dressing table or other piece of furniture in readiness for use when required.

The primary object of the invention is to provide a face powder feeder adapted to use exclusively loose powder to the exclusion of any block or cake of compressed powder which is always hard to replace by another block or cake having the same dimensions, said loose powder being, as is well known, easily procurable everywhere.

A further object of the invention is to provide a face powder feeder adapted to permit the escape of only the exact quantity of powder that must be picked up by a usual puff whereby no powder can be spilled off the feeder or puff which, while keeping the feeder tidy and unstained by powder, precludes any loss of powder.

A still further object of the invention is to provide a face powder feeder which while employing loose powder can never become choked by the same and permits the powder to be readily extracted from the feeder by the exertion of a very limited stress without any risk of the powder clogging into cake form and preventing proper operation of the feeder either in box form or in cabinet form.

A still further object of the invention is to provide a face powder feeder of simple mechanism that is cheap to manufacture and to assemble and is most reliable in use even in the long run.

Still a further object of the invention is to provide a face powder feeder of smart appearance which, being composed of a minimum number of parts that are cheap to manufacture, permits making to be carried out on an industrial scale while making it possible to decorate each powder feeder to suit the particular taste of every different user.

With these and such other objects in view as will incidentally appear hereinafter, the invention comprises the novel construction, combination and operation of parts that will now be described, reference being had to the accompanying drawing wherein are shown, by way of examples, several embodiments of same.

Figure 1 is a diametrical sectional view of a face powder feeder in the form of an ordinary powder box, constituting a first embodiment of the invention, assuming the box to be closed.

Figure 2 is a top plan view of the face powder box shown in Figure 1, assuming the same to be opened out for use.

Figure 3 is a fragmentary top plan view of the face powder box shown in Figure 1.

Figure 4 is an axial sectional view of a face powder feeder in cabinet form comprising a powder storing and feeding unit, and constituting the second embodiment of the invention.

Figure 5 is a sectional plan view on the line 5—5 of Figure 4, a slight additional detail being illustrated.

Reference being first had to the first embodiment as shown in Figures 1 to 3, 1 designates the body or container part of the box and 2 the lid or cover fitted with a mirror 3 (Fig. 2) held in position by an annular flange 4, a hinge 5 connecting the body 1 and lid 2.

In the container part 1 of the box is fitted a perforated or apertured plate 6 so embossed as to present an annular rib 7, the apertures of said plate being preferably arranged in the form of offset slots 8 disposed at right angles to one another, said slots being in the present embodiment so cut in the material of the plate 6 as to form elongated spouts opening sequentially anticlockwise for a purpose which will appear hereafter.

The lower part of the container 1 is encompassed by a cup 9 advantageously knurled or otherwise roughened on its outer peripheral surface for providing a better grip to the user's fingers and fitted centrally on its inner bottom face with a stud 10, fixed thereto or formed therewith, to which is re-

movably held by a pin 11 a serpentine or spirally-shaped rake or blade 12 formed by a strip of metal or other suitable material disposed edgewise in gentle frictional contact with the bottom 1^a of the container part 1 of the box. This serpentine rake is shown as made up of two helical curves delineating on each side of the centre a flaring entrance 12^a, a throttled portion 12^b and a belly or bulging portion 12^c. However the serpentine rake might have similar curved or angular shapes of different contours. The inner face of the bottom 1^a of the container 1, i. e. the face in contact with the rake 12 may 15 be smooth but is advantageously roughened in any approved way for example by scratching it with emery paper or by lining it with a non-smooth material such as fabric 1^b, for the purpose of preventing the powder 20 from becoming caked or from simply sliding freely over the bottom of the box under the action of the rake. The rakes moving over the roughened or fabric bottom act to effectively feed the powder at all times.

25 The space 13 between the perforated or apertured plate 6 and the mirror 3 is adapted to accommodate a puff (not shown) of known type. The face powder is loosely contained in the space between the plate 6 and the bottom 1^a of the container part 1 of the box.

30 The operation of this face powder box will be readily understood: By manually rotating the cup 9 anticlockwise as shown by the full line arrow in Figure 3, the serpentine 35 rake 12 fixed thereto through the stud 10 and pin 11 gathers the mass of face powder contained in the space between the bottom 1^a of the container 1 centrally, the powder penetrating (as shown by the dot and dash 40 line arrow in Fig. 3) into each flaring entrance 12^a, then passing through each throttled portion 12^b where its passage is, as it were, regularized and finally reaching the belly portion 12^c on each side of the centre 45 whence it is ejected upwardly through the slots of the plate 6, whereby a quantity of face powder proportional to the angular displacement of the cup 9 with respect to the container 1 emerges from the spout-like slots 50 8 and can be readily picked up by the puff (not shown) and then transferred onto the user's face in the usual way. Thanks to the special outline of the rake 12, the current of powder swept by the rake being throttled 55 at 12^b can not be unduly compressed into the belly portion 12^c and can not therefore get into cake form and hinder proper operation.

60 Reference being now had to the second embodiment of the invention as shown in Figures 4 and 5, this structure is adapted to be used at home for example on a dressing table whereas the box shown in Figures 1 to 3 is adapted to be carried in a hand bag.

65 As shown in Figure 4, the structure comprises a casing 15 which may be made of

wood, metal or any other suitable material and aesthetically decorated in any approved way. This casing is closed by a bottom plate 16 removably held by screws 17 or like securing means and furnished with a top partition 18 hollowed at one place to accommodate a cylindrical tank 19 adapted to store a certain quantity of face powder. This tank is closed at its upper end by a removable lid 20 and at its lower end by a horizontal dia- 75 phragm 21 held between the side walls of the casing 15. This diaphragm is recessed on a portion of its surface to provide a side opening of suitable size 22 in the bottom of the tank 19 for a purpose that will appear 80 hereafter. Centrally of the powder tank 19 passes an upwardly extending spindle 23 fitted at its top end with a knob 24 which may serve, as illustrated, for supporting a face cream box 25 of usual structure and furnished at its lower end with a rake 26 pinned thereto as at 27, said rake engaging the bottom surface of the tank 19. The spindle 23 passes through the diaphragm 21 85 and has keyed thereon a pinion 28 meshing with a pinion 29 keyed upon a spindle 30 which passes upwardly through said dia- 90 phragm and projects into the recessed portion thereof to carry a rake 31 of helical serpentine or other throttled curved or angu- 95 lar outline such as the one shown in Figure 3. The rake 31 is pinned to the spindle 30 as at 32 and so sized as to have a certain amount of overlap with the rake 26, the two rakes being thus, as it were, imbricated for a 100 purpose that will appear hereafter.

At a slight distance above the serpentine 105 rake 31 is arranged a perforated or apertured plate 33 advantageously formed with spout-like slots 34 as the apertured plate shown in Figure 2. The plate 33 is conveniently held by a ledge 35 screwed to the partition 18. Just above the apertured plate 33 is arranged a housing 36 held in a further hollowed portion of the partition 18 and covered by a removable lid 37 which may conveniently carry a small box 38 containing for example a cake of agglomerated face powder and a cake of rouge. In the housing 36 is accommodated a puff P of usual shape.

110 The partition 18 may be formed on its upper face with a depression 39 for receiving a stick of rouge (not shown). A pinion 40 meshing with the pinion 28 (Figure 5) and operated by a knob 41 may be provided for permitting to actuate the device from two different positions or through a reduction gear to limit the stress.

115 The operation of this face powder feeder will be readily understood: The face powder being stored, as aforesaid, in the tank 19, by causing the rake 26 to rotate about its spindle 23, a quantity of powder proportional to the angular motion of said rake is fed through the opening 22. At the same time, owing to 120

the action of the gear 28—29 the serpentine rake 31 is rotated in a direction reverse to that of the rake 26 whereby the powder contained in the chamber, preferably provided with a roughened bottom surface, in which the rake 31 rotates emerges through the spout-like slots 34, the quantity of powder thus fed out being automatically made good by the powder fed through the opening 22 whereby the rake 31 constantly remains imbedded in a substantially unchanged mass of powder and its angular motion always causes the same quantity of powder to be fed out through the slots 34 whence it can be picked up by the puff P in the usual way. By this arrangement, the user of the feeder can at any time accurately regulate the quantity of powder to be picked up by the puff, the powdering operation of the face being thus made easier and more uniform while no powder can become spilled and wasted.

It will be understood that the invention is not limited to the embodiments shown which are merely illustrative thereof. Numerous constructional details might be changed without departing from the spirit of the subjoined claims. Thus for example the shape of the rakes might be simplified or complicated provided they are adapted for gathering the powder centrally and pushing it upwardly through the slots while preventing it from clogging into cage form. The form and number of the slots and the gear connecting the rakes in the second embodiment may also vary as will be readily conceived by anyone skilled in the art.

What I claim is:

1. A face powder feeder comprising, in combination, a powder container, an apertured plate closing said container, a serpentine rake mounted for rotation upon itself with respect to the container so as to feed up the powder through the apertures in the plate, said serpentine rake delineating at least one channel having a flaring entrance, an intermediate throttled portion and an inner bulging portion, and means located outside the container for rotating the rake.

2. A face powder feeder comprising, in combination, a powder container, an apertured plate closing said container, a serpentine rake mounted for rotation upon itself with respect to the container so as to feed up the powder through the apertures in the plate, said serpentine rake being formed of two edgewise helical strips frictionally contacting with the bottom of the container and delineating two oppositely directed channels each having a flaring entrance, an intermediate throttled portion and an inner bulging portion, and means located outside the container for rotating the rake.

3. A face powder feeder comprising, in combination, a powder container, an apertured plate closing said container, the aper-

tures in this plate being in the form of offset slots arranged at right angles to one another, a serpentine rake mounted for rotation upon itself with respect to the container so as to feed up the powder through the slots in the plate, said serpentine rake being formed of two edgewise helical strips frictionally contacting with the bottom of the container and delineating two oppositely directed channels each having a flaring entrance, an intermediate throttled portion and an inner bulging portion, and means located outside the container for rotating the rake.

4. A face powder feeder comprising, in combination, a powder container having a rough bottom, an apertured plate closing said container, the apertures in this plate being in the form of offset perpendicular slots, a serpentine rake mounted for rotation upon itself with respect to the container so as to feed up the powder through the slots in the plate, said serpentine rake being formed of a double edgewise helical strip frictionally contacting with the rough bottom of the container and delineating two oppositely directed channels each having a flaring entrance, an intermediate throttled portion and an inner bulging portion, and means located outside the container for rotating the rake.

5. A face powder feeder comprising, in combination, a powder container, an apertured plate closing said container, the apertures in this plate being in the form of offset perpendicular slots formed as spouts opening in the same angular direction, a serpentine rake mounted for rotation upon itself with respect to the container so as to feed up the powder through the slots in the plate, said serpentine rake being formed of a double helical strip frictionally engaging edgewise the bottom of the container and delineating two symmetrical channels both opening in the same direction as the spout-like slots and each having an outer flaring entrance, an intermediate throttled portion and an inner bulging portion, and means located outside the container for rotating the rake in the aforesaid direction.

6. A face powder feeder comprising, in combination, a shallow powder container, a slotted plate closing the container, a cup snugly encompassing the container and centrally fitted with a stud journaled in the bottom of the container, a serpentine rake pinned upon the stud of the cup for rotating with respect to the container and feeding up the powder through the slotted plate, said serpentine rake being formed of a double helical strip frictionally engaging edgewise the bottom of the container and delineating two symmetrical channels each having an outer flaring entrance, an intermediate throttled portion and an inner bulging portion, and a lid connected to the container by a hinge.

7. A face powder feeder comprising, in

combination, a shallow powder container, a mirror-carrying lid connected to the container by a hinge, an apertured plate closing said container, the apertures in this plate being in the form of offset perpendicular slots formed as spouts opening in the same angular direction, a serpentine rake mounted for rotation upon itself with respect to the container so as to feed up the powder through the slots in the plate, said serpentine rake being formed of a double helical strip engaging edgewise the bottom of the container and delineating two symmetrical channels both opening in the same angular direction as the spout-like slots and each having an outer flaring entrance, an intermediate throttled portion and an inner bulging portion, a gear associated with the spindle and housed in the space between the diaphragm and the bottom of the casing, a powder tank supported by the diaphragm and connected by an opening in the latter with the container, a second spindle associated with the gear and carrying an operating knob, said second spindle axially traversing the powder tank, and a rake fixed upon the last-named spindle adjacent the bottom of the tank, said second rake slightly overhanging the first rake to sweep the powder from the tank into the container through said opening.

8. A face powder feeder comprising, in combination, a shallow powder container having a rough bottom, a mirror-carrying lid connected to the container by a hinge, a cup snugly encompassing the container and centrally fitted with a stud journaled in the bottom of the container, a removable plate closing the container and formed with offset perpendicular slots shaped as spouts all opening in the same angular direction, and a serpentine rake pinned upon the stud of the cup for rotating with respect to the container and feeding up the powder through the slots of the plate, said rake being formed of a double helical strip engaging edgewise the bottom of the container and delineating two symmetrical channels both opening in the same angular direction as the spout-like slots and each having an outer flaring entrance, an intermediate throttled portion and an inner bulging portion, a space being reserved between the slotted plate and lid when closed for housing a puff.

9. A face powder feeder comprising, in combination, a shallow powder container, an apertured plate closing the container, a serpentine rake mounted for rotation upon itself on a central spindle passing through the bottom of the container, said serpentine rake delineating at least one channel having an outer flaring entrance, an intermediate throttled portion and an inner bulging portion, a gear associated with the spindle, a second spindle associated with the gear and carrying an operating knob, a powder tank communicating by a bottom opening with the container and traversed axially by the last-named spindle, and a rake fixed upon the latter spindle adjacent the bottom of the tank, said second rake slightly overhanging the first rake to sweep the powder from the tank into the container through the said opening.

10. A face powder feeder comprising, in combination, a casing internally fitted with an intermediate horizontal diaphragm, a shallow powder container recessed in the dia-

phragm, a removable plate closing the container and formed with offset perpendicular slots shaped as spouts all opening in the same angular direction, a serpentine rake mounted for rotation upon itself on a central spindle passing through the diaphragm, said serpentine rake being formed of a double helical strip engaging edgewise the diaphragm and delineating two symmetrical channels both opening in the same angular direction as the spout-like slots and each having an outer flaring entrance, an intermediate throttled portion and an inner bulging portion, a gear associated with the spindle and housed in the space between the diaphragm and the bottom of the casing, a powder tank supported by the diaphragm and connected by an opening in the latter with the container, a second spindle associated with the gear and carrying an operating knob, said second spindle axially traversing the powder tank, and a rake fixed upon the last-named spindle adjacent the bottom of the tank, said second rake slightly overhanging the first rake to sweep the powder from the tank into the container through said opening.

11. A face powder feeder comprising, in combination, a casing internally fitted with an intermediate horizontal diaphragm and a partition located parallel to said diaphragm and in contact therewith, a shallow powder container recessed in the diaphragm and having a rough bottom surface, a plate screwed to the partition to close the container and formed with offset perpendicular slots shaped as spouts all opening in the same angular direction with respect to the centre of the container, a serpentine rake mounted for rotation upon itself on a central spindle passing through the diaphragm axially of the container, said serpentine rake being formed of a double helical strip engaging edgewise the rough bottom surface of the container and delineating two symmetrical channels both opening in the same angular direction as the spout-like slots and each having an outer flaring entrance, an intermediate throttled portion and an inner bulging portion, a gear associated with the spindle and housed in the space between the diaphragm and the bottom of the casing, a powder tank supported by the diaphragm in a hollowed portion of the partition and communicating by an opening in the diaphragm with the powder container, a second spindle associated with the gear and carrying an operating knob, said second spindle axially traversing the powder tank, a rake fixed upon the last-named spindle adjacent the bottom of the tank, said second rake slightly overhanging the first rake to sweep the powder from the tank into the container through said opening, and a puff-receiving housing located above the slot.

- ted plate in a hollowed portion of the partition.
12. A face powder feeder comprising in combination, a powder container, an apertured plate closing said container, and a rake mounted for rotation about an axis located substantially centrally of the container and at right angles to the bottom of the container and to the apertured plate, said rake having an arm or arms extending from said axis to near the periphery of the container, said arms being of nearly the width of the powder space between the bottom of the container and the under side of the apertured plate and acting, when rotated, to feed the powder directly upward through the apertures in said plate.
13. A face powder feeder comprising in combination, a powder container, an apertured plate closing said container, and a rake mounted for rotation about an axis located substantially centrally of the container and at right angles to the bottom of the container and to the apertured plate, said rake having an arm or arms extending from said axis to near the periphery of the container, said arms acting, when rotated, to feed the powder directly upward through the apertures in said plate, said apertures being in the form of slots so cut in the material of the plate as to form spouts opening in the direction of rotation of the rake.
14. A face powder feeder comprising in combination, a powder container, an apertured plate closing said container, said container having a roughened surface on the inside of the bottom thereof, a rake mounted for rotation over said roughened surface so as to feed up the powder through the apertures in the plate, said rake being formed to provide powder receiving recesses between the axis of rotation and the ends of the rake arms, and means for rotating the rake.
15. A face powder feeder comprising in combination, a powder container, an apertured plate closing said container, said container having a rough fabric covering fixed on the inside of the bottom thereof, a rake having members movable over said fabric for feeding the powder directly upward through the apertures in the plate and means for moving the rake with respect to said fabric covered bottom.
16. A face powder feeder comprising in combination, a powder container, a plate for closing said container having apertures disposed in circular alinement between the center and periphery of said plate, a rake mounted for rotation upon itself with respect to the container so as to feed up the powder through apertures in the plate, said rake having powder collecting recesses travelling in substantial alinement with said apertures when the rake is rotated, and means for rotating the rake.

17. A face powder feeder comprising in combination, a powder container having a fabric covering for the inside of the bottom thereof, a plate for closing said container having apertures disposed in circular alinement between the center and periphery of said plate, a rake mounted for rotation upon itself with respect to the container so as to feed up the powder through the apertures in the plate, said rake having powder collecting recesses travelling in substantial alinement with said apertures when the rake is rotated, and means for rotating the rake.

18. A face powder feeder comprising in combination, a powder container, an apertured plate closing said container, a rake mounted for rotation upon itself with respect to the container so as to feed up powder through the apertures in the plate, said rake comprising a metal strip mounted with its edges adjacent respectively to the bottom of the container and the underside of the apertured plate and bent to provide powder gathering recesses, and means for rotating the rake.

19. A face powder feeder comprising in combination, a powder container having a hole in the bottom thereof, a stud rotatably mounted in said hole, the end of the stud projecting into the container being slotted, a powder feeding rake formed of a bent metal strip mounted in said slotted stud, an apertured plate closing the container, and means for rotating said stud and rake.

20. A face powder feeder comprising in combination, a powder container having a hole in the bottom thereof, a stud rotatably mounted in said hole, a powder feeding rake formed of a bent metal strip mounted on the inner end of said stud, an apertured plate closing the container, and means for rotating said stud and rake comprising a cup enclosing the lower part of the container and engaging the outer end of said stud.

21. A face powder feeder comprising in combination, a powder container having a hole in the center of the bottom thereof, the inside of said bottom being covered with fabric, an apertured plate closing said container and a rake for feeding powder through the apertures in said plate, said rake comprising a metal strip set edgewise with respect to the bottom of the container, and formed to provide powder collecting recesses adapted to travel under the apertures in the plate when the rake is rotated about its axis, a stud mounted in the hole in the bottom of the container and fixed to said rake, and means for rotating said stud and rake.

In testimony whereof I affix my signature.

FELIX JOSEPH VICKI.
